UNITED STATES PATENT OFFICE.

VANCE SHEARER, OF NEW YORK, N. Y., ASSIGNOR TO BLUBLAZE MOTOR SPECIALTIES CORP., OF LONG ISLAND CITY, NEW YORK, A CORPORATION OF NEW YORK.

IGNITION TIMER FOR INTERNAL-COMBUSTION ENGINES.

Application filed November 4, 1921. Serial No. 512,702.

To all whom it may concern:

Be it known that I, VANCE SHEARER, a citizen of the United States, residing in the borough of Manhattan, city, county, and 5 State of New York, have invented an Improvement in Ignition Timers for Internal-Combustion Engines, of which the following is a specification.

My invention relates to timers for controlling the ignition in multiple cylinder internal combustion engines, and particularly to the means for supporting and carrying the brush or movable contact block employed in such devices, being an improvement 10 upon the invention shown and claimed in my copending application filed April 4th, 1921, Serial No. 458,459, its objects being to lessen the cost of manufacture, facilitate the assembling of the brush and its carrier, and to provide a more secure holder 15 for the brush.

The details of the invention are herein-after particularly described.

In the accompanying drawing:

Fig. 1 is an inner end view of a timer embodying my invention, the shaft being in section.

Fig. 2 is a vertical section on the broken line 2—2 of Fig. 1.

Fig. 3 is a face view of the brush carrier detached, and

Fig. 4 is an enlarged sectional view taken on the broken line 4—4 of Fig. 3.

Similar reference characters denote like parts throughout the several views.

Referring to the drawing 10, indicates the body of the timer which is substantially hollow, and externally of a shape similar to the present standard Ford timer, and is 40 provided with the usual lug 11, having an opening 12, to receive the connection for adjustment to advance or retard the spark. This body is preferably of insulating material molded or pressed to shape having an 45 angular raceway 13, into which are seated quadrantly spaced fixed contact blocks 14, 15, 16, and 17, which are preferably pressed into place at the time of molding the body member, the outer surfaces of such contact blocks being flush with the surface of the raceway 13. Two metallic blocks 18 and 19 are also set into the raceway 13, but not extending to the surface thereof.

Spaced binding posts 20 and 21 are 55 mounted on the top of the body member 10,

and their terminals 22 and 23 pass through openings in said body and come into contact with the two fixed upper contact blocks 14 and 15.

The binding posts 24 and 25 for connection with the two lower contacts 16 and 17, are also mounted upon the top of the body 10, between the binding posts 20 and 21.

Conductor wires or strips 26 and 27 pass 60 from the lower contact blocks 16 and 17 to the contact blocks 18 and 19, into contact with which the terminals 28 and 29 of the binding posts 24 and 25, are brought, these terminals passing through openings in the 70 body 10.

The wires or strips 26 and 27, are preferably pressed into place at the time of molding the body member, and extend past the upper contact blocks 14 and 15, but insulated therefrom.

30 indicates the timer shaft, one end of which extends into the hollow body 10.

The carrier for the brush or movable contact 31, comprises a circular disk or plate 32, having a central hub 33, keyed or otherwise fixed to the shaft 30, within the hollow body 10. The outer edge of the disk is preferably provided with an outwardly turned annular flange 34. This flanged 80 disk prevents oil reaching the brush or the raceway and fixed contacts thereon.

The disk has a thickened portion 35, extending from the hub 33, to the periphery of the disk, that portion adjacent the edge 90 of the disk on its front surface being of the greatest thickness and having a central opening 36, which is enlarged below the front surface of the disk forming an annular shoulder 37 within the opening at the top, 95 below which shoulder the opening is screw-threaded.

The brush or movable contact 31 fits loosely into the smaller part of the opening 36, and is provided with an annular flange 100 38, at its rear end, which flange takes against the shoulder 37, thus limiting the projection of the brush through said opening.

A hollow plug 39, threaded on its exterior is screwed into the threaded portion of the opening 36, there being a spiral spring 40, inserted into the hollow of the plug, which spring bears against the flanged end of the brush 31, and normally holds the brush projected through the smallest por- 105 110

tion of the opening 36; the hollow of the plug 39, is of slightly greater diameter than the flange on the brush, so that when the spiral spring 40, is compressed by the brush 5 in riding over the raceway 13, the rear end of the brush passes into the hollow of the plug, providing for a resilient bearing of the brush upon the raceway and fixed contacts.

A lock nut 41 may be employed upon the 10 end of the shaft 30, forward of the carrier hub 33.

I claim as my invention.

1. In an ignition timer, the combination 15 of a body having an interior annular raceway, a rotary shaft extending into the body, a circular plate fixed to said shaft and having a threaded recess adjacent its edge with an opening therein of smaller diameter forming an interior annular shoulder in the 20 end of said recess, a flanged brush projecting through said opening with its flange bearing against said shoulder, a hollow exteriorly threaded plug screwed into said recess, and a spiral spring within the hollow of said plug with one end bearing upon the flanged end of the brush.

2. In an ignition timer, the combination 30 of a body having an interior annular raceway, a rotary shaft extending into the body, a circular plate provided with a hub keyed to said shaft and having a thickened portion adjacent its edge at one point with a threaded recess at the rear end, an opening 35 in the front of smaller diameter than the recess whereby an interior annular shoulder

is formed within the recess, a flanged brush projecting through said opening with its flange bearing against said shoulder, a hollow exteriorly threaded plug screwed into said recess, and a spiral spring within the hollow of said plug bearing upon the flanged end of the brush. 40

3. In an ignition timer, the combination 45 of a hollow body of insulating material interiorly rabbeted forming an annular raceway, spaced fixed contacts seated in said raceway flush with its surface, metallic blocks set into said raceway below its surface, binding posts whose terminals engage certain of the fixed contacts, binding posts 50 whose terminals engage said metallic blocks intermediate the first named binding posts, conductors extending from said metallic blocks into contact with the remaining fixed contacts, a rotary shaft extending into the body, a circular plate fixed to said shaft covering the opening in the rear of the body and having a threaded recess adjacent its 55 edge with an opening therein of smaller diameter forming an interior annular shoulder in the inner end of said recess, a flanged brush projecting through said opening with its flange bearing against said shoulder, a hollow exteriorly threaded plug screwed into 60 said recess, and a spiral spring within the hollow of said plug with one end bearing upon the flanged end of the brush. 65

Signed by me this 26th day of October, 1921.

VANCE SHEARER.
